ATTORNEY.

UNITED STATES PATENT OFFICE.

HENRY BRUNT, OF BALTIMORE, MARYLAND.

DESIGN FOR A PLATE.

SPECIFICATION forming part of Design No. 28,840, dated June 14, 1898.

Application filed May 6, 1898. Serial No. 679,961. Term of patent 3½ years.

To all whom it may concern:

Be it known that I, HENRY BRUNT, a citizen of the United States, residing at Baltimore, in the State of Maryland, have invented and produced a new and original Design for Plates, of which the following is a specification.

The illustration in the drawing shows a plate with my design.

The essential feature of the design comprises two general features, to wit: first, three circular or ring bands *a b c*, concentric with respect to each other and located at or near the plate-rim. Each of the three bands is of a contrasting color. In the drawing these bands are shown as white and black; but in the article as manufactured the outer one is red, the next white, and the inner one blue. Second, a marine scene showing a representation of a war vessel and located in the center of the plate and within the three circular bands.

The marine scene is on the representation of a sheet of canvas unrolled. Above the sheet is an urn, from which vapors are arising, and an eagle with spread wings and holding in its beak a streamer on which letters may be placed. Below the sheet is the representation of a shield having stars and stripes and a base or foreground comprising wheat-stalks, crossed swords, and war munitions.

Having thus described my design, what I desire to secure by Letters Patent is—

The design for a plate herein shown and described.

In testimony whereof I affix my signature in the presence of two witnesses.

HENRY BRUNT.
